RAIL FLAW DETECTOR CAR

George Lester Jones, Garden City, N. Y., assignor
to Sperry Products, Inc., Brooklyn, N. Y., a corporation of New York

Application March 8, 1934, Serial No. 714,621

11 Claims. (Cl. 175—183)

This invention relates to rail flaw detector cars adapted to travel on railroad tracks and detect fissures inside the rails. More particularly, the invention relates to the Sperry rail flaw detector car wherein a detector mechanism is suspended from each side of the car to cooperate with the respective rail. Such suspended mechanisms are normally biased outwardly against the gauge side of the rail and it has been found that on approaching a frog the mechanism which is supported on a carriage riding on the rail sometimes tended to enter the turnout track of the frog when the car itself was travelling on the main track. This caused derailment and in some instances complete destruction of the carriage supporting the detector mechanism.

It is a principal object of my invention, therefore, to provide a device which will permit the flaw detector mechanisms to pass safely through frogs without passing to the wrong side of the facing point of the frog which would tend to derail and even destroy the detector mechanism.

Further objects and advantages of this invention will become apparent in the following detailed description thereof.

In the accompanying drawings,

Fig. 1 is a vertical section through a portion of a Sperry rail flaw detector car showing the detector mechanism suspended therefrom.

Fig. 2 is a section taken substantially on the line 2—2 of Fig. 1 and showing my invention applied to the detector mechanism.

Fig. 3 is a section taken substantially on the line 3—3 of Fig. 2.

Fig. 4 is a front elevation showing a modified form of my invention.

Fig. 5 is a view largely diagrammatic showing the control mechanism included in my invention.

Fig. 6 is a view largely diagrammatic showing a modified form of control mechanism.

Referring to the drawings, there is disclosed in Fig. 1 the Sperry rail flaw detector mechanism as applied to a Sperry rail flaw detector car. A portion of the car body 10 is disclosed, within which is supported a generator G for supplying current to the rail by means of sets of brushes 11 and 12 to establish an electro-magnetic field surrounding the rail. The flux in said field will be uniform as long as there are no flaws in the rail, but when a flaw is present the flux in said field is distorted. Such distortion of the field is detected by means of a pair of induction coils 15 spaced in tandem along the rail. Said coils are of equal inductance and oppositely wound so that normally as the car travels along the rail they cut a constant and equal number of lines of force.

On entering a region of flaw, one coil will cut a different number of lines of force than the other to generate a differential E. M. F. which, after being suitably amplified, may be caused to op-

erate any suitable indicator such as a recorder. The said coils are mounted in a housing 16 carried by a detector carriage 17 adapted to ride on the rail by means such as wheels 18. Said detector carriage is in turn supported on a current brush carriage 20 by means of loosely fitting bolts 21 and springs 22 which permits the detector carriage 17 to move independently of carriage 20 and to adjust itself to irregularities in the rail surface. The current brush carriage 20 supports the current brushes 11 and 12 and may be supported on the rail by means of wheels 25, which wheels are toed outwardly as shown in Fig. 2 so as normally to bias the current brush carriage outwardly into firm engagement with the gauge side of the rail. The carriage may be biased outwardly also by means of springs 26 (see Fig. 4), said springs assisting the toeing out action of the wheels in maintaining the current brush carriage constantly against the gauge side of the rail. The current brush carriage 20 is supported on the car body by means of piston rods 28 connected to pistons 29 operating in fluid pressure cylinders 30 mounted in a Cardan suspension 35, 36, 37 which permits the carriage 20 to swing laterally with respect to the rail. The current brush 20 is normally held in raised position by means of retractile springs 31 and cables 32, 33, but when it is desired to lower the carriage into engagement with the rail, fluid pressure, such as compressed air, is admitted to the cylinders 30 to depress the pistons 29 and thus lower the carriage against the action of the retractile springs.

The mechanism shown in Fig. 1 is duplicated at each side of the track so that one of said mechanisms coacts with the respective rail. By referring to Fig. 2 it will be seen that if each of these mechanisms were supported independent of each other as has heretofore been the practice, and said detector car travelled in the direction of the arrow shown in Fig. 2, then on approaching a frog there would be a tendency, because of the fact that each carriage is biased outwardly against the gauge side of the rail as described above, for said wheels 25 to enter the turnout side 40 of the frog. Since the car itself travels along the undeviating, or main, portion of the track on the side 39 of the frog, the carriage 20 would be moved outwardly to cause eventual derailment, and, as has been the case in several instances heretofore, complete destruction of the said carriage.

To remedy the above difficulty I provide the following construction which will prevent the current brush carriage from riding into the turnout side of the frog when the car is on the main track:

Since only one side of the track is affected by a frog while the other side is straight, unbroken

track, I make use of this fact by locking the two carriages at the respective sides of the track together so that in effect there is formed a 4-wheel truck which, like the 4-wheel trucks of the car body 10, or of any car, will not be affected by entering a frog. This is due to two reasons. In the first place, the carriage 20' on the straight track is biased outwardly by means of the toed-out wheel and the springs, as heretofore described, and by locking carriage 20 to carriage 20' the latter will counteract any tendency of carriage 20 to ride into the turnout path 40 of the frog.

In the second place, the straight track is usually provided with a guard rail R' which begins in advance of the frog on the opposite rail so that carriage 20' is locked by the guard rail against inward movement, and therefore by locking carriage 20 to carriage 20', carriage 20 is locked against further outward movement and thus locked against movement into the turnout path 40.

The means which I provide for locking together the carriages at opposite sides of the car when a frog is approached may take the form shown in Fig. 2 which comprises rods 50 pivotally supported at 51 on one of the carriages and coacting with sleeves 52 pivotally supported at 53 on the other of said carriages. The rods normally are free to move within said sleeves so that said carriages are normally free to move independently of each other. On approaching a frog, however, such freedom of movement may be interrupted and the sleeves locked firmly to the rods. For effecting such locking, the following construction may be employed: The ends of sleeves 52 may be slit in several places at 54 and a strap 55 may be provided. The ends of said strap may be wrapped firmly around the end of said respective sleeve to lock said sleeve to the rod 50 by means such as a piston 57 operating in cylinder 58 to which fluid pressure is adapted to be supplied from any suitable source by means of tube 59. When said fluid pressure is discharged into the cylinder the piston is depressed to pull the piston rod 60 inwardly, said rod being fastened to one end 61 of the strap so as to carry said end toward the end 62 fixed to cylinder 58 and through which piston 60 operates, and thus lock the strap around the sleeve. In this manner both sleeves 52 are locked to the rods 50 and the two carriages 20 and 20' are locked together as a unit. The ends of said strap are normally moved apart by means such as spring 63.

An alternative method of locking the two carriages together is disclosed in Fig. 4. Instead of rod 50 operating in sleeves 52 there may be provided a cable 65 connecting the two carriages, said cable extending from fixed guide roller 66 and a movable guide roller 67, said rollers being supported on the car body by means of a frame 68. The movable guide roller 67 is normally in lowered position and in such position the cable takes up the dotted line position to provide slack therein so that the carriages 20 and 20' may move independently of each other. When, however, a frog is approached the guide roller 67 is moved upwardly to the full line position by means such as fluid pressure cylinders 58' (see Fig. 5). Nected at its other end to the piston 64 extending from the fluid pressure device 58. When fluid pressure is allowed to enter the said cylinder 58 the piston rod 64 is drawn upwardly to raise the roller 67 and thus take out the slack of the cable 65 as shown by the full line position of said cable,

With the slack taken out of the cable, the two carriages 20 and 20' are locked together as a unit and it is impossible for the distance between them to increase as would be necessary if one of the carriages entered the turnout side of the frog. The lever 69 is normally held in lowered position by means such as a spring 75.

It has been described hereinbefore that detector carriage 17 is mounted on current brush carriage 20 by means of bolts 21 extending loosely into the said carriage so as to permit movement of said detector carriage 17 independent of the movement of carriage 20. It may occur on approaching a frog that the detector carriage 17 may tend to ride into the wrong side 40 of the frog and thus be carried outwardly, which would destroy the mounting of said detector carriage on the current brush carriage. To prevent such a condition from occurring, I may provide straps 80 on carriage 20 adapted to engage the upper ends of bolts 21 when fluid pressure is introduced into fluid pressure cylinders 58' (see Fig. 5).

The control of the means for locking the carriages 20 and 20' together as a unit, either by the Fig. 2 or Fig. 4 form of the invention, may be manual under the control of the operator, in part manual and in part automatic as described below. The manual control may consist of a switch S (see Fig. 5) adapted to be closed by the operator on the car when a frog is approached. Said switch controls a circuit including a battery B in which is located a relay 79 which actuates a valve 81 controlling the supply of fluid pressure to the cylinders 58 and 58'. If it is desired to operate said valve 81 semi-automatically, there may be mounted on the car body a finger 82 projecting downwardly into the path of switch rail SR so that on approaching a frog, finger 82 will strike said rail in advance of the frog and will swing about its pivot 83 to close a set of contacts 84 to operate the valve 81. Contacts 84 are connected in parallel in the circuit of battery B and when it is desired to operate the locking means semi-automatically switch S' is opened so that the circuit through relay 79 then lies through contacts 84. On approaching a frog the operator closes switch S but this does not energize relay 79, the latter being energized only when contacts 84 are closed. Whenever hand operation is desired, switch S' is closed and switch S is opened, the operator controlling the locking device solely by the latter switch.

Instead of a fluid pressure supply such as compressed air for operating the locking means, that is the straps which encircle the sleeves, I may employ electro-magnetic devices which may take the form of solenoids 85, 85', the cores of which may be the rods 66 corresponding to the rods 66 of the Fig. 3 form. Here, too, the operator may control the energization of all of said relays 85, 85', solely by switch S, or such operation may be effected jointly by the operator actuating switch S and rod 62 engaging the switch rail.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without

interfering with the more general results outlined, and the invention extends to such use.

Having described my invention, what I claim and desire to secure by Letters Patent is:

- 5 1. In combination with a rail flaw detector car having a car body, a carriage at each side thereof movable laterally with respect to the rail, each carriage supporting flaw detector mechanism and having wheels engaging the respective rail, means 5 for preventing said carriages from entering the turnout of a frog when said car is on the main track, said means comprising means independent of said car-body for locking the said carriages together.
- 10 2. In combination with a rail flaw detector car having a car-body, a carriage at each side thereof movable laterally with respect to the rail, each carriage supporting flaw detector mechanism and having wheels engaging the respective rail, means 10 for preventing said carriages from entering the turnout of a frog when said car is on the main track, said means comprising means independent of said car-body for locking said carriages against outward movement with respect to each other.
- 15 3. In combination with a rail flaw detector car having a car-body, a carriage at each side thereof movable laterally with respect to the rail, each carriage supporting flaw detector mechanism and having wheels engaging the respective rail, means 15 for preventing said carriages from entering the turnout of a frog when said car is on the main track, said means comprising means independent of said car-body for interconnecting said carriages to limit the maximum distance between them.
- 20 4. In combination with a rail flaw detector car having a carriage at each side thereof movable laterally with respect to the rail, each carriage supporting flaw detector mechanism and having wheels engaging the respective rail, means 20 for preventing said carriages from entering the turnout of a frog when said car is on the main track, said means comprising means for locking the said carriages together and means engageable with the switch rail of the frog for rendering said locking means effective.
- 25 5. In combination with a rail flaw detector car having a carriage at each side thereof movable laterally with respect to the rail, each carriage supporting flaw detector mechanism and having wheels engaging the respective rail, means 25 for preventing said carriages from entering the turnout of a frog when said car is on the main track, said means comprising means for locking the said carriages together, means whereby said locking means is normally maintained ineffective, and means engageable with the switch rail of the frog for rendering said locking means effective.
- 30 6. In combination with a rail flaw detector car having a carriage at each side thereof movable laterally with respect to the rail, each carriage supporting flaw detector mechanism and having wheels engaging the respective rail, means 30 for preventing said carriages from entering the turnout of a frog when said car is on the main track, said means comprising a cable interconnecting said carriages, means whereby said cable is normally maintained slack to permit relative outward movement between said carriages, and means for eliminating said slack to lock said carriages against outward movement on approaching the frog.
- 35 7. In combination with a rail flaw detector car having a carriage at each side thereof movable laterally with respect to the rail, each carriage supporting flaw detector mechanism and having wheels engaging the respective rail, means 35 for preventing said carriages from entering the turnout of a frog when said car is on the main track, said means comprising a cable interconnecting said carriages, a movable pulley for normally supporting said cable in slack position to permit relative outward movement between said carriages, and means for moving said pulley to eliminate said slack and lock said carriages against outward movement on approaching a frog.
- 40 8. In combination with a rail flaw detector car having a carriage at each side thereof movable laterally with respect to the rail, each carriage supporting flaw detector mechanism and having wheels engaging the respective rail, means 40 for preventing said carriages from entering the turnout of a frog when said car is on the main track, said means comprising a cable interconnecting said carriages, a movable pulley for normally supporting said cable in slack position to permit relative outward movement between said carriages, and means engageable with the switch rail of a frog for moving said pulley to eliminate said slack and lock said carriages against outward movement on approaching a frog.
- 45 9. In combination with a rail flaw detector car having a carriage at each side thereof movable laterally with respect to the rail, each carriage supporting flaw detector mechanism and having wheels engaging the respective rail, means 45 for preventing said carriages from entering the turnout of a frog when said car is on the main track, said means comprising a cable interconnecting said carriages, a movable pulley for normally supporting said cable in slack position to permit relative outward movement between said carriages, and means engageable with the switch rail of a frog for moving said pulley to eliminate 40 said slack and lock said carriages against outward movement on approaching a frog.
- 50 10. In combination with a rail flaw detector car having a carriage at each side thereof movable laterally with respect to the rail, each carriage supporting flaw detector mechanism and having wheels engaging the respective rail, means 50 for preventing said carriages from entering the turnout of a frog when said car is on the main track, said means comprising a sleeve carried by the carriage at one side, a rod carried by the carriage at the other side and extending into said sleeve, clamping means for clamping said sleeve to said rod, said clamping means being normally ineffective so that said rod moves freely in said sleeve, and means for rendering said clamping means effective on approaching a frog.
- 55 11. In combination with a rail flaw detector car having a carriage at each side thereof movable laterally with respect to the rail, each carriage supporting flaw detector mechanism and having wheels engaging the respective rail, means 55 for preventing said carriages from entering the turnout of a frog when said car is on the main track, said means comprising a sleeve carried by the carriage at one side, a rod carried by the carriage at the other side and extending into said sleeve, clamping means for clamping said sleeve to said rod, said clamping means being normally ineffective so that said rod moves freely 60 in said sleeve, and means engageable with the switch rail of a frog for rendering said clamping means effective on approaching a frog.
- 60 12. In combination with a rail flaw detector car having a carriage at each side thereof movable laterally with respect to the rail, each carriage supporting flaw detector mechanism and having wheels engaging the respective rail, means 60 for preventing said carriages from entering the turnout of a frog when said car is on the main track, said means comprising a sleeve carried by the carriage at one side, a rod carried by the carriage at the other side and extending into said sleeve, clamping means for clamping said sleeve to said rod, said clamping means being normally ineffective so that said rod moves freely 65 in said sleeve, and means engageable with the switch rail of a frog for rendering said clamping means effective on approaching a frog.
- 65 13. In combination with a rail flaw detector car having a carriage at each side thereof movable laterally with respect to the rail, each carriage supporting flaw detector mechanism and having wheels engaging the respective rail, means 65 for preventing said carriages from entering the turnout of a frog when said car is on the main track, said means comprising a sleeve carried by the carriage at one side, a rod carried by the carriage at the other side and extending into said sleeve, clamping means for clamping said sleeve to said rod, said clamping means being normally ineffective so that said rod moves freely 70 in said sleeve, and means engageable with the switch rail of a frog for rendering said clamping means effective on approaching a frog.
- 70 14. In combination with a rail flaw detector car having a carriage at each side thereof movable laterally with respect to the rail, each carriage supporting flaw detector mechanism and having wheels engaging the respective rail, means 70 for preventing said carriages from entering the turnout of a frog when said car is on the main track, said means comprising a sleeve carried by the carriage at one side, a rod carried by the carriage at the other side and extending into said sleeve, clamping means for clamping said sleeve to said rod, said clamping means being normally ineffective so that said rod moves freely 75 in said sleeve, and means engageable with the switch rail of a frog for rendering said clamping means effective on approaching a frog.
